UNITED STATES PATENT OFFICE.

DURELL, ORVILLE PEASE, OF MANNINGHAM, BRADFORD, ENGLAND.

SPINNING-MACHINE.

No. 806,086.

Specification of Letters Patent.

Patented Nov. 28, 1905.

Application filed March 28, 1904. Serial No. 200,415.

To all whom it may concern:

Be it known that I, DURELL, ORVILLE PEASE, a citizen of the United States of America, residing at and whose post-office address is 25 5 Parkview Terrace, Manningham, Bradford, county of York, England, have invented certain new and useful Improvements in Spinning-Machines; and I do hereby declare the following to be a full, clear, and exact description of the invention, such as will enable others skilled in the art to which it appertains to make and use the same.

This invention for improvements in spinning-machines relates more especially to machines for spinning woolen and worsted threads, and has for its object to enable a spinning-machine to produce finer and sounder threads; and it consists in increasing the number of alternate stretchings and releasings given to the roving at each revolution of the twisting-head, so that the roving can be drawn finer and at the same time of more uniform gage without danger of breaking by reason of uneven and violent drawing, and to increase 15 the twist near to the twisting-head, so that the roving will be softer in comparison between the twisting-head and delivery-rollers, enabling a still further drawing and a still further increased twist to be given to the yarn, so that 20 25 30 a sounder and finer thread can be produced. According to this invention the roving enters the axis of the twisting-head as it comes from the delivery-rollers at an angle, and on the top of the head are two approximately opposite pins, so that at each revolution of the twisting-head two alternate stretchings and releasings are given to the yarn, so as to give a practically continuous stretching and releasing action, thereby eliminating the disadvantages of 35 40 45 relatively widely separated stretchings and releasings.

A still further improvement consists in a support or deflector arranged between the delivery-rollers and the twist-head and over 50 which the yarn passes and is deflected before reaching the twisting-head. The deflector or support is adjustable, so that the amount of deflection, and consequently the pressure of the yarn on the deflector, can be varied. The 55 effect of the deflector is that an excess of or harder twist is given to the yarn between the twisting-head and the deflector and a decrease of or softer twist between the deflector and the delivery-rollers, so that the speed of the twisting-head can be increased. The effect of 55 the alternate stretchings and releasings is

therefore increased between the deflector and delivery-rollers.

In the accompanying sheet of illustrative drawings, Figure 1 is a side elevation, partly in section, of the head of a spinning-machine. Fig. 2 is a plan, and Fig. 3 a front elevation, of the same.

The apparatus comprises the delivery-rollers *a*, the twist-head *b*, and the drawing-rollers *c*. The head *b* is provided on its top with two axially-aligned pins *d* at approximately opposite ends of a diameter. A support or deflector *e* is fixed on the frame *f*, in which the head *b* rotates and bears on the yarn between the delivery-rollers *a* and the twist-head *b*. The yarn *g* passes through the delivery-rollers *a*, over the deflector *e*, through the twist-head *b* to the drawing-rollers *c*. At each revolution of the twist-head the pins *d* come into contact with and stretch the yarn *g* and then release it, so that two alternate stretchings and releasings are given to the yarn for each revolution of the twist-head. The effect of this construction is to give a uniform and practically continuous stretching and releasing action, resulting in a finer and more evenly gaged thread than is the case where the stretch and release take place at appreciable intervals or, say, only once in the revolution of the twister-head. The yarn bearing on the deflector *e* causes the twisting action of the twist-head to be stronger on the part *g'* of the yarn between the jaws of the head and the deflector, and therefore causes the stretching action of the pins to be greater on the part *g* of the yarn between the deflector and the delivery-rollers as compared with the stretching action of the pins on the part *g'* of the yarn.

What I claim, and desire to secure by Letters Patent, is—

In a spinning-machine and in combination, delivery-rollers, a twister-head having a plurality of yarn-engaging pins to give a succession of alternate stretchings and releasings to the yarn at each revolution of the twister-head, a rigid yarn-deflector between the said delivery-rollers and said twister-head, means for adjusting said deflector to vary the angle of the delivery of the yarn to the twister-head, and drawing-rollers.

In testimony whereof I have affixed my signature in presence of two witnesses.

DURELL, ORVILLE PEASE.
